DESIGN FOR A TEXTILE FABRIC

Eugene Irving Hanson, New York, N. Y.

Application October 23, 1936, Serial No. 65,436

Term of patent 3½ years

To all whom it may concern:

Be it known that I, Eugene Irving Hanson, a citizen of the United States, residing in New York, county and State of New York, have invented a new, original, and ornamental Design for a Textile Fabric, for which the following is a specification, reference being had to the accompanying drawing, forming part thereof, wherein—

The figure is a plan view of a textile fabric showing my new design, in which the design unit has been outlined in dot and dash lines.

I claim:

The ornamental design for a textile fabric, substantially as shown and described.

EUGENE IRVING HANSON.
